JOHN E. HOBBS, OF NORTH BERWICK, MAINE.

Letters Patent No. 86,155, dated January 26, 1869.

IMPROVED GASOMETER.

The Schedule referred to in these Letters Patent and making part of the same.

To all persons to whom these presents may come:

Be it known that I, JOHN E. HOBBS, of North Berwick, in the county of York, and State of Maine, have invented a new and useful or improved Gasometer; and do hereby declare the same to be fully described in the following specification, and represented in the accompanying drawings, of which—

Figure 1 denotes a side elevation,

Figure 2, an end view,

Figure 3 is a longitudinal section, and

Figure 4 is a transverse section of it.

This gasometer is intended for the use of chemists, and particularly for railway-carriages, its purpose being for holding gas, and emitting it under the pressure of springs, as hereinafter described.

In the drawings—

A denotes a metallic plate or tablet, having underneath it another such plate or follower, C.

The edges of each of the plates A and C are bent or flanged, so as to form channels *a a*, to receive the edges of a flexible tube, T, made of India rubber, or any other gas-proof equivalent.

Before the edges of the tube are inserted in the channels, such edges have strips, *b b*, of India rubber, or some other suitable compressible material, cemented to them on the inner and outer surfaces of the tube. This tube, as shown in the drawings, is rectangular in horizontal section.

After the edges, prepared with the packing-strips, have been inserted in the channels of the parts A and C, the sides of each of the channels are to be pressed together, or one toward the other, so as to make, with the packing, an air or gas-tight joint.

The two parts A C, with the flexible tube, will then be very like an ordinary bellows, and may be used to great advantage as a gasometer.

Two bars, D D, are carried across the upper surface

of the part A, and project beyond its opposite edges, in manner as represented.

There are also two other such bars, E E, which are extended across the under surface of the follower C, and beyond its opposite edges.

Those portions of such bars which so project beyond the edges of the plate A and the follower C, are inserted within a series of elastic loops, F F F F, made of vulcanized India rubber, the whole being arranged in manner as represented.

While the cross-bars serve to strengthen the plates A and C, and support the elastic loops or springs, the latter, by their arrangement, are enabled to operate to good advantage in drawing the follower C toward the plate A, so as to effect the discharge of gas from the gasometer, as may be desired, when it may be supplied with gas.

I make no claim to the application of a board and weights to a gas-bag, for the purpose of expressing its contents.

What I claim is—

The improved gasometer, or the combination and arrangement of the cross-bars and the loop-springs with the plates A C and flexible tube T, or their equivalent, the whole being substantially as set forth.

Also, each of the plates A C, as made with the collapsible channels, to receive the edges of the flexible tube.

Also, the combination and arrangement of the elastic packing-strips with the flexible tube, and with the channelled plate applied to such packing and tube, as set forth.

JOHN E. HOBBS.
